ROTARY PUMP AND COMPRESSOR

Charles J. Wolff, San Antonio, Tex.

Application December 16, 1946, Serial No. 716,611

11 Claims. (Cl. 230—207)

1

The invention relates to a rotary mechanism for the compression of vapors and gases.

An object of the invention is the provision of a compression unit for gaseous fluids which obtains high compression efficiency.

Another object of the invention is the provision of a compressor in which the pressure differential between the high and low pressure sides of the compressor will serve to actuate a lubricating system for the compressor. This feature obviates the necessity of independent lubricating systems, with their frequent breakdowns and, being governed by the pressure differential on opposite sides of the compressor, will automatically provide greater lubrication when the compressor is laboring under high pressure differentials than when pressure differences are low which is as it should be since greater heat is generated with the high pressure differentials and a greater supply of lubricant is required for efficient operation of the compressor.

Another object of the invention is to provide a means of separating the lubricant from the compressed medium.

A further object of the invention is to obviate the condensation of the medium compressed in the lubricant which condensation normally results in low operating efficiency and improper lubrication of the compressor.

Another object of the invention is to provide a rotary mechanism adapted to receive and discharge a quantity of fluid.

Another object of the invention is to provide a rotary mechanism adapted to receive and discharge a quantity of fluid, and having a lubricating system operable as a function of the differential pressure between the receiving and discharge sides of the compressor.

A further object of the invention is to provide in combination, a rotary compressor, a lubricating system therefor, and separator means to separate the lubricant from the medium compressed.

It is a further object of the invention to provide a unit which is readily convertible from a compressor or vacuum pump to a pump for liquids with a minimum of alterations and changeover parts.

Other objects and advantages of the present invention will become apparent with a consideration of the following description and drawings wherein:

Fig. 1 is a vertical cross sectional view of an embodiment of the compressor, partly in elevation, taken on the line 1—1 of Fig. 2;

Fig. 2 is a vertical cross sectional view, partly in elevation, taken on the line 2—2 of Fig. 1;

2

Fig. 3 is a sectional view, partly in elevation, taken on the line 3—3 of Fig. 2;

Fig. 4 is an enlarged fragmentary sectional view of the compressor discharge valve means and the sealing means between the high and the low sides of the compressor being a fragmentary portion of the view shown in Fig. 1;

Fig. 5 is an enlarged isometric view of the sealing bushing between the inlet and outlet conduits of the compressor as the bushing appears when removed from the compressor.

In describing the construction of the invention, attention is invited to Figs. 1 and 2 wherein it will be observed that a compressor assembly denoted as 1 is shown as comprising a cylindrical member 1 provided with a central bore 2 and an offset bore 3 disposed in parallel relation thereto, and communicating therewith through a slot 4. Secured to each end of the cylinder 1 are the sealing plates 5 held in position by suitable means such as the screws 6. Adjacent the sealing plates 5 and secured to each end of the cylinder 1 by suitable means such as the screws 7 which pass entirely through the cylinder member from end to end, are the bearing plates 8 which form the support means for the bearings 9. An eccentric shaft, generally denoted by the numeral 10, is supported by the bearings 9 and is provided on its eccentric portion 11 with suitable bearings 12 which fit the concentric bores of a cylindrical piston element 13 in which the eccentric shaft 10 is free to rotate. A dome 14 which is clamped against one of the bearing plates 8 is held in engagement therewith by means of the screws 7 which secure the bearing plates to the ends of the cylinder 1. A second dome 15 is similarly held in engagement with the other bearing plate by suitable means such as the cap screws 16. The dome 15 is provided at its outer end with a bore and suitable sealing means, which will be described later, through which the driving end of the eccentric shaft 10 passes.

One side of the piston element 13 is provided with an axially extending groove 17 into which is slidably fitted a key element 18 passing through the slot 4 and having formed at its outer extremity a cylindrical portion 19. The cylindrical portion 19 is mounted for oscillating movement in the bore of a bushing 20 which is located in the bore 3 of the cylindrical member 1. The bushing 20 is held against rotation and firmly against the outer wall of the bore 3 by means such as the cap screws 21 threaded through the member 1 and into the bushing.

Thus, it will be seen that the key element 18 is free to oscillate in the slot 4 which in turn

oscillates the cylindrical portion 19 thereof in the bushing 20 in response to the gyratory motion of the piston element 13 caused by rotation of the eccentric shaft 10. The cylinder 1, the piston 13, the key element 18, and the bushing 20 are all the same length so that when the sealing plates 5 are in position leakage of fluid around their ends is lessened.

Referring to Figs. 4 and 5 it will be noticed that the bushing 20 is provided along one side with a longitudinal slot 4' which when the bushing is in assembled position coincides with the slot 4 between the bores 2 and 3. A cut recessed portion 22 extending partially around the periphery of the bushing 20 and substantially along its length serves as a means for establishing communication between the slot 4 and the fluid passages 23 and 24 respectively on opposite sides of the key element 18 and the bushing 20 in bore 3.

From the foregoing it is apparent that rotation of the eccentric shaft 10 in a counter-clockwise direction as seen in Fig. 1 will effect a counter-clockwise gyration of the piston element 13 which results in an intake of fluid from the fluid passage 23. This fluid is carried around the periphery of the piston element 13, the gyratory motion of the piston element serving to compress and discharge it through the slot 4, around the cut recessed portion 22, and into the discharge passage 24.

Located in the passage 24 closely adjacent the bushing 20 is a check valve 25 which is normally held in its seated position in an outwardly facing chamfer of the passage by the compression spring 26 both the valve and the spring being held in proper operating position by means of the valve guide 27 threadedly secured in the outer end of the passage 24 and provided with a suitable gasket 28 in order to prevent leakage of fluid therefrom. A discharge passage 29 serves to establish communication between the passage 24 and the exterior of the compressor.

In order to balance the piston 13 and reduce its weight, a bore 30 therein as shown in Figs. 1 and 2 is provided. A counterweight 31 is secured to the eccentric shaft 10, this counterweight being located inside the dome 15 with its center of gravity diametrically opposed to the eccentric 11. The counterweight thus balances the eccentric 11 and the piston 13. The bore of the dome 15 through which the eccentric shaft 10 passes is provided with a cover plate 32 having a central bore for the passage of the eccentric shaft 10 and a finished inside face as sealing means with the seal 33 which rotates with the eccentric shaft 10 and is held in close sliding relation with the finished face of the cover plate 32 by means of the compression spring 34 interposed between the seal 33 and the hub of the counterweight.

A driving pulley 35 connected by means of the belt 36 to any suitable power source furnishes the driving means for the eccentric shaft 10. The spokes 37 of the pulley 35 are preferably in the form of fan blades in order to provide air circulation for cooling the compressor while in operation.

From the foregoing description it will be observed that from the seal 33, on the right hand end in Fig. 2, to the bearing plate 8 on the left hand end of the cylinder 1 the entire compressor is enclosed with the exception of the passages 23 and 24 and the inlet from the coil 48. For this reason it is apparent that no fluids except those passing through one or the other of the passages 23 or 24 or the coil 48 can gain en-

trance or escape from the compressor. This is of particular importance in dealing with the compression of refrigerants. In the compression of refrigerants, in a closed system, it is common knowledge that the high pressure refrigerant should be kept from contact with the lubricant in the reservoir of the compressor in order to prevent condensation of the refrigerant in the lubricant. From an inspection in Figs. 1 and 2 it is obvious that when the eccentric shaft 10 is rotating in a counter-clockwise direction, as seen in Fig. 2, the passage 23 will be the intake, or low pressure passage to the compressor, while the passage 24 is the high pressure outlet from the compressor. The dome 14 is always under low pressure while the dome 15, the bearings 9 and 12, and the piston 13 are subject to a pressure which will vary from high to low depending upon operating conditions as will be described.

In operation, the driving pulley 35 is connected to a suitable power supply which serves to rotate the eccentric shaft 10. The rotation of this shaft causes the piston element 13 to oscillate in the cylindrical member 1. The outside surface of the piston 13 moves tangentially around the inner wall of the cylindrical member 1. Since lubricant is present in the cylinder, a traveling fluid seal is formed in the cylinder as the piston moves along the inner wall.

As this fluid seal passes the inlet port 23, the piston element 13 moves away from the cylindrical member 1 due to the eccentric movement of shaft 11, a void is created adjacent the inlet port.

This void in turn causes a decrease in pressure on the inlet side of the cylinder so as to draw in a quantity of fluid to be compressed. As the piston continues to travel around the cylinder wall, the fluid is caused to travel ahead of the seal. This charge of fluid moves toward the outlet port 24 and is discharged therethrough.

The dome 14 is provided with a suitable lubricant 52 to the approximate level indicated in Fig. 2 and the gas, or vapor, to be compressed is admitted to the dome 14 through the inlet conduit 38 and enters the upper end of the conduit 40 above the level of the lubricant passing downwardly therethrough and entering the cylinder 1 through the passage 23. In Figs. 2 and 3 it will be noted that the juncture of the conduit 40 with the inlet passage 23 is below the surface of the lubricant and that a small metering hole 41 is provided in a wall of the conduit 40 proximate its lower extremity. The purpose of this metering hole is to admit a small quantity of lubricant to the interior of the conduit 40 from where it will be drawn into the inlet passage 23 and subsequently into the interior of the bore 2 of the cylinder 1. The lubricant thus admitted to the cylinder serves as a lubricant and seal for the periphery of the piston 13 and any excess lubricant admitted therethrough will be discharged through the discharge passage 24 into the discharge conduit 39.

As a matter of practical knowledge, it has been found in practice that this admission of lubricant to the interior of the compressor results in a substantial increase in the operating efficiency of the compressor especially in the compression of gases or vapors where slip is a troublesome factor.

While the admission of lubricant to the interior of the compressor is of advantage from a standpoint of operating efficiency it is obvious that the lubricant discharged through the dis-

charge conduit 39 would soon exhaust the lubricant from the compressor were not some means provided for reclaiming the lubricant so discharged. Referring to Figs. 1, 2, and 3, it will be observed that the discharge conduit 39 leads to an oil saver 42 which consists of an insulated cylinder sealed at both ends. Fluids emerging from the conduit 39 enter a screened strainer 43 which permits passage of gaseous portions but upon which particles of lubricant in the fluid adhere and gravitate downwardly finally dropping off the lower end of the screen into the bottom of the oil saver 42. The lubricant-free gaseous portions pass from the oil saver through the conduit 44, and in the case of refrigerants, are carried directly to a condenser.

This flow of fluid into the oil saver, the separation of lubricant therefrom and passage of lubricant-free fluid to the condenser continues until sufficient lubricant has collected in the bottom of the oil saver to raise the float 45 lowering the valve 46 and permitting the lubricant from the bottom of the oil saver to flow into the conduit 47. It is to be noted that the level of the float 45 is so located in the oil saver that the oil level inside the cylinder must always be above the lower end of the conduit 47 before the float 45 will open the valve 46. Thus, only lubricant can enter the conduit 47 from the oil saver 42.

Since the temperature inside the oil saver is comparatively high, the oil leaving the oil saver in the conduit will also be at a high temperature and in order to cool this lubricant before putting it to use again, the conduit 47 is formed into a series of coils 48 about the compressor, the end of such coil being connected into the dome 15. The lubricant in dome 15 has access to the piston 13 in cylinder 1 through the bearings 9 and 12. Excess lubricant in the cylinder 1 will be forced between the ends of the piston 13 and the sealing plates 5 thereby providing a lubricating and sealing film between the ends of the piston and the sealing plates.

The only pressure existing inside the dome 15 during operation of the unit is due to the entrance of lubricant through the conduit 47 from the oil saver 42 and this pressure will build up to proximate the pressure in the discharge conduit 39 while the compressor is running and when the compressor stops, the lubricant inside the piston 13 will slip past the ends of the piston and through the inlet passage 23 to the interior of the dome 14. In fact, as previously stated during the time the compressor is running, there is a continual flow of lubricant from the dome 15 past the ends of the piston 13 to form a sealing means for the ends of the piston.

In order to prevent a hydraulic lock of the key element 18 in the groove 17 passages 50 establishing communication between the bottom of the groove 17 and the low pressure side of the cylinder 1 are provided whereby any lubricant entrapped beneath the key element 18 will be discharged therethrough.

Particular attention is invited here to the construction illustrated in Figs. 4 and 5 wherein the arrangement of the bushing 20, the sealing element 18 between the high and low pressure sides of the compressor and its pivot bearing 19, the undercut 22 of the bushing communicating with the passages 23 and 24, and the placement of the check valve 25 are shown in detail. Another feature of the greatest importance in economical construction and which contributes greatly in promoting efficiency of operation is the struc-

ture illustrated in Fig. 2 wherein the central cylindrical element 1 constitutes a body to which the sealing plates 5, the bearing plates 8, and the domes 14 and 15 are secured.

Broadly the invention contemplates a compressor, which, in combination with the automatic and continuous lubricating and sealing provisions hereinabove described, comprise a unit adaptable to production manufacturing methods which is economical in cost, highly efficient in operation and easily serviced in the field.

The invention claimed is:

1. A rotary eccentric compressor comprising a compressor assembly, said assembly including, a cylinder, a low pressure oil reservoir at one end of said cylinder, an inlet port for said cylinder, communicating means including lubricant metering means, between said low pressure oil reservoir and said inlet port, an outlet port for said cylinder communicating with the exterior thereof and connecting with separating means for separating lubricant from the discharged gas, a conduit from said separating means leading to the point of application of said gas, a high pressure oil reservoir, a conduit from said separating means leading to the interior of said high pressure oil reservoir, a conduit from the point of application of said gas to said low pressure oil reservoir so that oil will be drawn into said compressor assembly as a function of the differential between said inlet and outlet ports, an eccentric shaft rotatably mounted and extending through said cylinder, a piston on said shaft, said piston being pivotally mounted in said cylinder so that as said eccentric shaft rotates said piston will move in tangential relation to said cylinder to first create a vacuum therein, such vacuum force serving to draw a gas through said inlet port into said cylinder to be compressed and discharged through said outlet port.

2. A rotary eccentric compressor comprising a compressor assembly, a low pressure reservoir at one end of said assembly, a high pressure oil reservoir at the other end of said assembly, said assembly including a cylinder, an inlet port for said cylinder communicating with said low pressure oil reservoir, an outlet port for said cylinder to the exterior thereof, an eccentric shaft rotatably mounted and extending through said cylinder, a piston on said shaft, said piston being pivotally mounted in said cylinder so that as said eccentric shaft rotates said piston will move in tangential relation to said cylinder to first create a vacuum therein, such vacuum force serving to draw a gas through said inlet port into said cylinder to be compressed and discharged through said outlet port, metering means connecting said low pressure reservoir and said inlet port so that oil will be drawn into said compressor assembly as a function of the differential pressure between said inlet and outlet ports, separate means connected on the outlet side of said compressor to separate the compressed gas from the oil, and conduit means to conduct the separated oil to said high pressure oil reservoir connected on said assembly.

3. In a rotary eccentric compressor, a pair of oil reservoirs, a compressor assembly therebetween, said assembly including a cylinder, an inlet port for said cylinder communicating with one of said reservoirs, an outlet port for said cylinder leading to the exterior thereof, an eccentric shaft rotatably mounted extending through said one of said reservoirs and said cylinder, a piston on said shaft, said piston being

pivotsly mounted in said cylinder so that as said shaft rotates the piston moves in tangential relation to said cylinder so as to first create a vacuum therein, such vacuum force tending to draw a medium in through said inlet port into said cylinder to be compressed and discharged through said outlet port, metering means connecting said one of said reservoirs to said inlet port for lubricating the moving parts of said compressor assembly as a function of the differential pressure between said inlet and outlet ports, the other of said reservoirs serving as an oil overflow receptacle.

4. In a rotor compression mechanism adapted to continuously receive a quantity of fluid to be compressed and then discharged therefrom, means to lubricate and aid in maintaining a seal between the compressing parts of such mechanism, said means being operable automatically as a function of the differential pressure between the receiving and discharge pressure of the fluid being compressed, said lubricating means comprising a low pressure lubricant reservoir on the low pressure side of said compressor mechanism, a high pressure lubricant reservoir on the high pressure side of said compressor mechanism, a lubricant and gas separating assembly, an inlet port for said compressor mechanism, an outlet port for said compressor mechanism, communicating means between said low pressure lubricant reservoir and said inlet port including orifice metering means for admitting lubricant to said inlet port, communicating means between said outlet port and said lubricant and gas separating assembly, a conduit from said separating assembly to said high pressure lubricant reservoir, communicating means from said high pressure lubricant reservoir to said compressor mechanism whereby lubricant is admitted to the interior and abutting portions of the compressor mechanism, a conduit from said lubricant and gas separating assembly to the point of application of the compressed gas, and a conduit from said low pressure lubricant reservoir to a source of supply.

5. In a rotary compressor adapted to continuously receive a quantity of fluid to be compressed and discharged therefrom, a lubricating system for the compressor operable by the pressure differential between the receiving and discharging pressure of the fluid being compressed so that the compressor will automatically be provided with greater lubrication when the pressure differential is greater, said lubricating means comprising a low pressure lubricant reservoir on the receiving side of said compressor, a high pressure lubricant reservoir on the discharge side of said compressor, a lubricant and gas separating assembly, an inlet port for said compressor, an outlet port for said compressor communicating means between said low pressure lubricant reservoir and said inlet port including orifice metering means for admitting lubricant to said inlet port, communicating means between said outlet port and said lubricant and gas separating assembly, a conduit from said separating assembly to said high pressure lubricant reservoir, communicating means from said high pressure lubricant reservoir to said compressor whereby lubricant is admitted to the interior and abutting portions of the compressor, a conduit from said lubricant and gas separating assembly to the point of application of the compressed gas, and a conduit from said low pressure lubricant reservoir to a source of supply.

6. In a rotary compressor adapted to continu-

ously receive a quantity of fluid to be compressed and discharged therefrom, a lubricating system for the compressor operable by the pressure differential between the receiving and discharge pressure of the fluid being compressed so that the compressor will automatically be provided with greater lubrication when the pressure differential is greater and so that the amount of lubrication will be decreased when the pressure differential decreases, said lubricating means comprising, a low pressure lubricant reservoir on the receiving side of said compressor, a high pressure lubricant on the discharge side of said compressor, a lubricant and gas separating assembly, an inlet port for said compressor an outlet port for said compressor, communicating means between said inlet port and said low pressure reservoir including orifice metering means for admitting lubricant to said inlet port, communicating means between said outlet port and said lubricant and gas separating assembly, a conduit from said separating assembly to said high pressure lubricant reservoir, communicating means from said high pressure lubricant reservoir to said compressor whereby lubricant is admitted to the interior and abutting portions of the compressor, a conduit from said lubricant and gas separating assembly to the point of application of the compressed gas, and a conduit from said low pressure lubricant reservoir to a source of supply.

7. A rotary mechanism adapted to receive and discharge a quantity of fluid comprising, a cylinder, an inlet port therefor, a low pressure lubricant reservoir on one side of said cylinder in communication with said inlet port, a high pressure lubricant reservoir on the other side of said cylinder, an outlet port for said cylinder leading to the exterior thereof, an eccentric shaft rotatably mounted and extending through said cylinder, a piston moveably mounted in said cylinder so as to move in tangential relation to said cylinder as said shaft rotates, metering means in said inlet port to furnish lubricant to the moving parts of the mechanism to form a seal thereof to obviate leakage of the fluid being compressed from said mechanism, separator means connected to said outlet port to separate the lubricant from the fluid discharged from the mechanism, float means in said separator means to effect passage of such separated lubricant from said separating means, a conduit from said separator means to said high pressure lubricant reservoir, communicating means between said high pressure lubricant reservoir and the interior of said cylinder, and passage means through the bearings of said cylinder to admit lubricant to the interior of said cylinder and the abutting ends of said piston and cylinder.

8. In a compression mechanism adapted to continuously receive a quantity of fluid to be compressed and discharged therefrom to lubricate the abutting compression mechanism parts of such mechanism, said means being operable as a function of the differential pressure between the receiving and discharge pressure of the fluid being compressed, said lubricating means comprising, a low pressure lubricant reservoir located on the inlet side of said compression mechanism and communicating with the inlet port thereof by conduit means for withdrawing low pressure fluid from said low pressure reservoir, metering means associated with said conduit below the level of lubricant in said low pressure reservoir for admitting a predeter-

75

mined amount of lubricant to the fluid being drawn into said compression mechanism, a fluid and lubricant separating means with said low pressure lubricant reservoir mechanism leading to the exterior thereof and communicating with said fluid lubricant separating means, a high pressure lubricant reservoir on the high pressure side of said compression mechanism, a conduit from said fluid and lubricant separating means to said high pressure lubricant reservoir, communicating means between said high pressure lubricant reservoir and the interior of said compression mechanism, and passage means through the bearings of said compression mechanism whereby high pressure lubricant is admitted to the interior and abutting portions of said compression mechanism.

9. In a rotary compressor adapted to continuously receive a quantity of fluid to be compressed and discharged therefrom, a lubricating system for the abutting compressor parts which is operable as a function of the pressure differential between intake and discharge of the compressor so that the compressor will be automatically provided with greater lubrication when the pressure differential is greater, said lubricating system comprising a low pressure lubricant reservoir located on the inlet side of said compressor and communicating with the inlet port thereof by conduit means for withdrawing low pressure fluid from said reservoir, metering means associated with said conduit below the level of lubricant in said low pressure for admitting a predetermined amount of lubricant to the fluid being drawn into said compressor, a fluid and lubricant separating means with said low pressure lubricant means, an outlet port for said compressor leading to the exterior thereof and communicating with said fluid and lubricant separating means, a high pressure lubricant reservoir on the high pressure side of said compressor, a conduit from said fluid and lubricant separating means to said high pressure lubricant reservoir, communicating means between said high pressure lubricant reservoir and the interior of said compressor, and passage means through the bearing of said compressor whereby lubricant is admitted to the interior and abutting portions of said compressor.

10. In a rotary compressor adapted to continuously receive a quantity of fluid to be compressed and discharged therefrom, a lubricating system for the abutting parts which is operable as a function of the fluid differential between the intake and discharge pressures of the compressor so that the compressor will be automatically provided with greater lubrication when the pressure differential is greater and so that the amount of lubrication will be decreased when the pressure differential decreases, said lubricating system comprising a low pressure lubricant reservoir located on the inlet side of said compressor and communicating with the inlet port thereof by conduit means for withdrawing low pressure fluid from said reservoir, metering means associated with said conduit below the level of lubricant in said low pressure reservoir for admitting a predetermined amount of lubricant to

the fluid being drawn into said compressor, a fluid and lubricant separating means with said low pressure lubricant reservoir, an outlet port for said compressor leading to the exterior thereof and communicating with said fluid and lubricant separating means, a high pressure lubricant reservoir on the high pressure side of said reservoir, a conduit from said fluid and lubricant separating means to said high pressure lubricant reservoir, communicating means between said high pressure lubricant reservoir and the interior of said compressor, and passage means through the bearings of said compressor.

11. A rotary eccentric compressor comprising a hollow cylinder, an eccentric shaft rotatably mounted and extending through said cylinder, means for rotating said shaft, heads for each end of said cylinder, said cylinder having a low pressure end and a high pressure end, a casing forming a lubricant reservoir at the low pressure end of said cylinder, a casing forming a lubricant reservoir at the high pressure end of said cylinder, a piston rotatably on said eccentric shaft said piston being pivotally mounted in said cylinder so that as said eccentric shaft rotates said piston will move in tangential relation to said cylinder, an inlet port on one side of said pivotal mounting, metering means between said inlet port and the interior of said low pressure lubricant reservoir casing beneath the level of the lubricant therein, a conduit from said inlet port metering means to a location above the level of the lubricant in said casing, an inlet port into the upper portion of said casing, an outlet port on the other side of said pivotal mounting, communicating means between said outlet port and the exterior of said cylinder, separator means connected with said outlet port for separating lubricant from the compressed fluid, a conduit from said separating means to the point of application of said compressed fluid, a conduit from said separating means to said low pressure lubricant reservoir casing, all of aforesaid components combining to form a system whereby the periphery of said cylinder and said piston are lubricated by lubricant drawn into the cylinder through the inlet port from the low pressure lubricant reservoir casing, and where the eccentric shaft bearings and abutting ends of said cylinder and said piston are lubricated by lubricant from said lubricant reservoir casing at the high pressure end of said cylinder.
